OTHER PUBLICATIONS Outlet cover on p. 27 of *New Equipment Digest*, Apr. 1993.*Primary Examiner*—Joel Sincavage*Attorney, Agent, or Firm*—Brinks Hofer Gilson & Lione**[57]****CLAIM**

I claim the ornamental design for an outdoor electrical outlet cover, as shown.

DESCRIPTION

FIG. 1 is a front perspective view showing my new design; FIG. 2 is a side view thereof, the opposite side view being a mirror image;

FIG. 3 is a front view thereof;

FIG. 4 is a rear view thereof;

FIG. 5 is a top view thereof;

FIG. 6 is a bottom view thereof;

FIG. 7 is a front perspective view showing a second embodiment of my design;

FIG. 8 is a side view of the embodiment shown in FIG. 7, the opposite side view being a mirror image;

FIG. 9 is a front view of the embodiment shown in FIG. 7;

FIG. 10 is a rear view of the embodiment shown in FIG. 7;

FIG. 11 is a bottom view of the embodiment shown in FIG. 7; and,

FIG. 12 is a top view of the embodiment shown in FIG. 7.
